UNITED STATES PATENT OFFICE

MAX MEIROWSKY, OF COLOGNE-EHRENFELD, GERMANY.

ELECTRIC CONDENSER.

1,010,936.

Specification of Letters Patent.

Patented Dec. 5, 1911.

Application filed March 3, 1909. Serial No. 481,549.

To all whom it may concern:

Be it known that I, MAX MEIROWSKY, a citizen of the German Empire, and resident of Cologne-Ehrenfeld, Germany, have invented certain new and useful Improvements in Electric Condensers, of which the following is a specification.

The present invention relates to electric condensers and the method for making the same, and has for its purpose to provide a condenser having the highest efficiency with the maximum compactness in structure; and which does not require a protecting casing.

The further purpose is in making the condenser of such design that the same may be manufactured by a single process and at comparatively little cost.

The article of the invention is shown in perspective in the accompanying drawing.

Referring to the figure in further detail *a* designates a strip of substantially hard and thick fibrous material, such as heavy paper, which is coated with shellac, resin, or other insulating substance. The sheet *a* is rolled into cylindrical form, in a manner hereinafter explained and interposed between the layers of the roll are separate sheets of tin-foil *b*. The alternate layers of tin-foil and paper thus constructed possess the firmness of wood or soft metal and need not therefore be incased. Constructing the condenser in tubular form has the further advantage that it is kept cool at all times, the central opening affording a natural air passage-way.

In manufacturing the article the strip of paper *a* is saturated with shellac, or resin, and then rolled upon a spindle. As the sheet is being thus wound sheets of tin-foil *b* are interposed between the layers thereof at regular intervals. The capacity of the condenser may be here determined by the number of tin-foil sheets interposed, and the space intervals between the sheets *i. e.*, by placing the sheets, during the winding, in close or distant succession. As the sheets *a* and *b* are being wound upon the spindle, the former sheet is subjected to the action of a heated mandrel which co-operates with the spindle as a pressing roller. The heating of the sheet *a* removes all dampness, and causes

the coating of shellac or resin to become semi-fluid. This latter condition effects to bring the several layers and the interposed sheets into an intimate and fixed relationship, and gives to the completed article such compactness and firmness as to not require an inclosing casing. The simultaneous winding and pressing of the paper sheet, under the conditions aforesaid, exerts such an effect on the di-electric inductive capacity of the paper that the same is several times as great as that of raw paper.

What I claim as my invention and desire to secure by United States Letters Patent is:

1. The process of manufacturing an electric condenser consisting in saturating a film of fibrous material with resinous substance, rolling the film upon a spindle while heating said film, and interposing sheets of tin foil between the layers of the roll during said winding.

2. The process of manufacturing an electric condenser consisting in first saturating a sheet of paper with shellac; second, rolling said sheet upon a spindle while in contact with a heated mandrel; third, interposing sheets of tin foil between the layers of the roll during the winding thereof.

3. The process of producing an electric condenser consisting in uniting by winding, fibrous material saturated with resinous substance, and interposed sheets of tin foil, and in simultaneously compressing and heating said elements when uniting them.

4. The process of manufacturing an electric condenser consisting in saturating a film of fabric with a resinous solution, rolling said film upon a spindle while in contact with a heated mandrel, and interposing strips of the foil located in relative positions corresponding to the tension and capacity to be developed in the condenser.

In testimony whereof I have signed my name to this specification in the presence of two subscribing witnesses.

MAX MEIROWSKY.

In presence of—

LOUIS VANDORY,
CARL HERMANN.
